UNITED STATES PATENT OFFICE.

LUDWIG SPÄNGLER, OF VIENNA, AUSTRIA-HUNGARY.

DOUBLE-DECKED VEHICLE.

1,085,504.

Specification of Letters Patent. Patented Jan. 27, 1914.

Original application filed May 21, 1913, Serial No. 769,030. Divided and this application filed October 10, 1913. Serial No. 794,526.

To all whom it may concern:

Be it known that I, LUDWIG SPÄNGLER, a subject of the Emperor of Austria-Hungary, residing at Vienna, Empire of Austria-Hungary, have invented certain new and useful Improvements in Double-Decked Vehicles; and I do hereby declare the following to be a full, clear, and exact description of the invention, such as will enable others skilled in the art to which it appertains to make and use the same.

My invention relates to a double decked vehicle and has for its object to improve the construction and increase the seat capacity of such vehicles.

The present application is a division of my prior application filed May 21st 1913, Ser. No. 769030.

In the annexed drawings: Figure 1 is a side elevation a plan of the lower deck a plan of the upper deck and a transverse section of a car embodying my invention. Fig. 2 shows similar views of a modification of the same. Fig. 3 shows similar views of an autobus embodying my invention. Fig. 4 shows similar views of a modification of the autobus illustrated by Fig. 3. Fig. 5 shows views similar to Fig. 1 of a further modification of my invention. Fig. 6 is an elevation of a modified tram car embodying my invention.

In order to reduce the total height of the vehicle as far as possible and to provide for a clear height of the passage ways on both decks permitting the passengers to stand and go upright, I employ on both decks transverse double benches opposing each other with the backs, the neighboring double benches on each deck being separated by a transverse passage way, and so stagger or arrange the double transverse benches on the two decks that the transverse passage ways on the one deck are vertically above or below the benches of the other, the floor of the upper deck being cut away under the benches on the same.

Fig. 1 shows such an arrangement in a railway or street car without a motor, the entrance and exit doors 2 being arranged at the sides in the central portion. From these doors leads a longitudinal passage way 11 along the side of the car to the stairs 1 from the lower deck to the upper deck and which are arranged at the ends of the cars. On both decks transverse double benches op-

posing each other with the backs are mounted and the neighboring double benches 12 of the lower deck are separated from each other by transverse passage ways 14 while on the upper deck the double benches 13 are separated from each other by transverse passage ways 15. The transverse passage ways 14, 15 lead into the longitudinal passage ways 11 and 16 respectively which are arranged on opposite sides of the car. The double benches 12, 13 on the two decks are staggered or arranged in such a manner that the transverse passage ways 14, 15 of one deck are vertically below or above the transverse double benches 13 or 12 respectively on the other deck, the floor of the upper deck being cut away under the benches 13. The clear height of the transverse passage ways of the lower deck is therefore equal to the distance between the two decks plus the height of the seats of the upper deck and this permits the reduction of the height of the lower deck and at the same time enables the passengers to stand and go upright. Thus the total height of the car is reduced. In order to obtain the required clear height of the passage way 11 of the lower deck, the part of the floor of the upper deck just above this passage way must be raised to a suitable extent. This is realized most advantageously by interposing seats between neighboring double benches of the upper deck and cutting away the floor under such seats as indicated in the drawings. The clear height of the upper floor must of course be sufficient to permit the passengers to stand upright. The part of the lower deck below the longitudinal passage way 16 of the upper deck is too low for a passage way, but it can be utilized for seats interposed between the transverse benches as shown in Fig. 1. Preferably on the upper deck an arrangement is used which leaves sufficient space for a single bench under which the floor of the upper deck is cut away for obtaining a passage way to the corresponding end bench of the lower deck as is shown in Fig. 1 or a single bench is provided at the end of the series in the upper deck above which a passage way leads to the end bench of the upper deck. The width of a double bench being in most cases notably greater than the width of the transverse passage way between two neighboring transverse

benches, the clear width of the transverse passage ways of the lower deck is greater in its upper part than in its lower part, whereby the danger of the passengers hurting themselves off rising briskly is greatly reduced. This arrangement offers moreover the advantage that the wheels may be conveniently located under double benches of the lower deck and that therefore the 10 floor of the lower deck may be located at an exceptionally low level which also contributes to the reduction of the total height of the car. If the longitudinal passage way on the lower deck comes above the 15 wheels a step or the like will have to be interposed into the same. If with this arrangement the entrance and exit doors are at the side the car can be run with only one particular end foremost. This drawback is 20 done away with by providing entrance and exit doors at the ends of the car.

In Fig. 2 the application of the invention to an electrically driven car is shown in which for more conveniently locating the 25 driving wheels and motors, the floor of the lower deck must be placed at a higher level at the ends of the car, while in the central portion it may be placed at a lower level. The entrance and exit door or doors 2 are in 30 this case located in the central portion and the passage way to the stairs 1 at the ends of the car is at one side of the same. A stop 17 is interposed in the passage way 11 between the central portion of the lower deck 35 and each of its end-portions and for reducing the height of this step, the floor of the lower deck may slope down from the said step to the center of the car. One or two steps of the two flight stairs 1 may lead to 40 the end platform 18 from which the second flight of the stairs leads to the upper deck. In Fig. 2 it is assumed that in the central portion of the car the distance between the floors of the two decks is sufficient to permit 45 the passengers to stand upright. The passage way of the lower deck may be at the same side of the car on the right and left hand side of the entrance and exit door or doors or it may be on one side of the car 50 at the right hand side of the said door and on the opposite side of the car at the left hand side of this door. The seats in the central portion of the lower and the upper deck may then be arranged at will; in the 55 end portions of the lower deck and in the portions of the upper deck above the same transverse double benches 12, 13 and transverse passage ways 14, 15 are arranged in the manner described above with reference 60 to Fig. 1. Also the floor of the upper deck above the longitudinal passage way 11 is placed at a higher level and utilized for seats between the transverse benches while 65 below the longitudinal passage way 16 of the upper deck seats are provided between

the transverse benches of the lower deck. The freedom of arranging the seats in the central portion of the lower deck permits providing entrance and exit doors on both sides of the car. I may also provide in the central portion of the lower deck longitudinal benches reaching as far as possible toward the ends of the car so that the lateral longitudinal passage way is short and begins near the end of the car. This facilitates entering and leaving the car.

In Fig. 3 the invention is shown as applied to an omnibus. The entrance and exit door 2 is at the rear platform 18 from which the stairs 2 lead to the upper deck and its longitudinal passage way 16 and from which also the longitudinal passage way 11 of the lower deck is reached. In all other respects the arrangement is the same as in the car shown in Fig. 1 or in the end portions of Fig. 2.

Fig. 4 illustrates a modification of the arrangement described with reference to Fig. 3. In this modification the entrance into the longitudinal passage way of the lower deck is in the center of the width of the platform 18. The longitudinal passage way 11 first runs between benches 21, 22 at the sides of the vehicle in the center or nearly in the center of the width of the same and then turns to one side and to the transverse passages 14. On the upper deck two longitudinal benches 23 with the backs opposing each other are arranged above the rear end of the passage way 11 of the lower deck. Of the two lateral passage ways 16 one is continued toward the front end of the vehicle up to the transverse passage ways 15. The floor of the upper deck is cut away under the double bench 23 in order to give the longitudinal passage way of the lower deck the required clear height, the floor of the lower deck is recessed under the benches 21, 23 for accommodating the rear wheels. If desired a foot rest 24 may be provided in front of one or both longitudinal benches under which foot rest the floor of the upper deck is cut away as is well known in the art. Similar foot rests may be provided on the lower deck as is indicated in dotted lines at 20 in Fig. 4. A similar arrangement may also be used in an electrically operated tram car such as shown in Fig. 2, that is to say, as illustrated in Fig. 6, a central or substantially central longitudinal passage way 26^a leads to the outer portion of the floor of the lower deck which is raised or situated at a higher level on account of the trucks, the floor of this passage way 26^a is at a lower level in the central portion of the car where the wheels are not in the way. Thus the required clear height may be obtained below the floor of the upper deck.

Fig. 5 illustrates how the invention may be applied to cars which are so broad that

there is sufficient space for a longitudinal passage way on both sides of the trucks. In this case the floor of the two longitudinal passage ways 11 and 19 of the lower deck 5 may be arranged at a level sufficiently low for obtaining the required clear height for these passage ways. The transverse benches 12 on the lower deck are located between the two longitudinal passage ways on a portion 10 of the floor sufficiently raised throughout its length for accommodating the wheels so that the transverse passage ways 13 are reached from the longitudinal passage ways 11 and 19 over steps. The transverse benches 14 of 15 the upper deck are arranged between two longitudinal passage ways 16, 26 located right above the passage ways 11, 19 of the lower deck. The double benches of the two decks are staggered as above described, 20 the floor of the upper deck being cut away under its benches. One of the longitudinal passage ways of the lower deck for instance 25 11 may extend over part of the length of the car only, seats being interposed between the remaining transverse double benches as shown in Fig. 4. Also one of the longitudinal passage ways of the upper deck may extend over part only of the length of the car or may be entirely dispensed with.

30 Claims:

1. In a double decked vehicle the combination of a lower deck and an upper deck, transverse double benches on both decks, transverse passage ways between neighboring 35 transverse double benches and longitudinal passage ways communicating with the said transverse passage ways on both decks, the transverse double benches and intervening transverse passage ways on one deck being staggered relatively to those on the other 40 deck and the floor of the upper deck being cut away under the transverse benches on the upper deck.
2. In a double decked vehicle the combination of a lower deck and an upper deck, 45

transverse double benches on both decks, transverse passage ways between neighboring transverse double benches and longitudinal passage ways communicating with the said transverse passage ways on both decks, 50 the transverse double benches and intervening transverse passage ways on one deck being staggered relatively to those on the other deck and the floor of the upper deck being cut away under the transverse benches on 55 the upper deck, at least part of a longitudinal passage way on one deck being on the side of the vehicle opposite to that on which a longitudinal passage way on the other deck is situated and seats being interposed between the transverse double benches at the ends of the transverse passage ways remotest from one of the longitudinal passage ways, the floor of the upper deck being cut away under such interposed seats on such upper 60 deck.

3. In a double decked vehicle the combination of a lower deck and an upper deck, transverse double benches on both decks, transverse passage ways between neighboring transverse double benches and longitudinal 70 passage ways communicating with the said transverse passage ways on both decks, the transverse double benches and intervening transverse passage ways on one deck being staggered relatively to those on the other deck and the floor of the upper deck being cut away under the transverse benches on the upper deck and the floor of at least part 75 of the longitudinal passage ways of the lower deck being at a lower level than the floor of the transverse passage ways of the lower deck.

In testimony whereof, I affix my signature, in presence of two witnesses.

LUDWIG SPÄNGLER.
